METHOD OF REFINING CRUDE OLEFINIC NITRILES

Erwin L. Carpenter, Old Greenwich, Harold S. Davis, Riverside, and Oscar F. Wiedeman, Stamford, Conn., assignors to American Cyanamid Company, New York, N. Y., a corporation of Maine

Application October 31, 1939, Serial No. 302,072

13 Claims. (Cl. 202—42)

1

The present invention relates to the refining of crude olefinic nitriles, that is, those nitriles which may be hydrolyzed to olefinic acids.

The dehydration of an alkylene cyanohydrin yields equi-molecular proportions of the corresponding olefinic nitrile and water, which may be collected as two partially miscible layers. Upon separation, the upper layer is found to be predominantly nitrile containing some water, while the lower is predominantly water containing some nitrile.

For instance, in the production of acrylonitrile from the dehydration of ethylene cyanohydrin, the upper nitrile layer of the product is found to contain from 4 to 5% of water whereas the lower or water layer may contain from 5-8% of nitrile.

Therefore, in the manufacture of the olefinic nitriles, it is highly essential to have at hand a method whereby the crude product can be refined to a pure dry state.

The principal object of the present invention resides in a method of refining a crude olefinic nitrile wherein the product may be readily obtained free from water. Another important object is to provide an olefinic nitrile in a pure state by a method requiring only simple apparatus with high efficiencies.

The applicants have discovered that olefinic nitriles saturated with water, distill azeotropically in such proportions that the percentage by weight of water in the distillate exceeds the solubility of water in the nitrile, and consequently the distillate separates into two layers. Hence a large proportion of the water may be removed from the saturated solution by placing a water separator in the head of a reflux column and continuously refluxing the solution. As the water is removed from the solution, the percentage of water in the distillate decreases and finally becomes equal to the solubility of the water in the nitrile. At this point, the water separator in the column is removed and the small portion of water remaining in the nitrile removed by distillation. This procedure has the advantage of reducing the volume of the fore-runnings to a very considerable extent.

Referring to the accompanying drawings,

Fig. 1 is a diagrammatic flow sheet of a preferred method of carrying out the invention;

Fig. 2 shows a modified method, and

Fig. 3 illustrates still another alternative system.

As shown in Fig. 1, a quantity of a crude olefinic nitrile, such as, for example, a crude product of acrylonitrile and water produced, for instance,

2

by the dehydration of ethylene cyanohydrin, is permitted to separate into two layers. The lower layer of water containing from 5 to 8% of acrylonitrile is withdrawn and shaken with about twice its volume of xylene. The mixture separates into two layers upon standing. The lower layer, being principally water, is withdrawn and discarded. The upper xylene layer containing the acrylonitrile is united with the initial acrylonitrile layer containing from 4 to 5% water. The xylene displaces a small amount of water from the mixture. This water layer is withdrawn and returned to an initial water layer containing some acrylonitrile. The remaining layer of acrylonitrile, xylene and dissolved water is fractionated in a fractionating still operating with substantially total reflux of the nitrile. The water and nitrile form an azeotropic mixture in the reflux column. Over a temperature range of from 70 to 75° C. this reflux mixture is condensed at the reflux head and allowed to stratify into two layers. The upper nitrile layer flows back into the still while the lower water layer is withdrawn and returned to an initial water layer containing some acrylonitrile. A small amount of nitrile polymer forms during the fractionation. A fraction of wet acrylonitrile is then removed from the still content at a temperature of from 75 to 77° C. and returned to an initial acrylonitrile layer containing water. The dry acrylonitrile is fractionally distilled from the still content at 77-78° C. The still residue of polymer and xylene is filtered and the latter returned to the cycle.

As illustrated by the flow sheet of Fig. 2, a quantity of a crude olefinic nitrile such as, for example, a crude product of acrylonitrile and water, produced as above, is permitted to separate into two layers. The lower layer of water containing from 5 to 8% of acrylonitrile is withdrawn and shaken with about twice its volume of xylene. The mixture upon standing separates into two layers. The lower layer being principally water is withdrawn and discarded. The acrylonitrile is removed from the upper xylene layer by distillation. The still residue of polymer and xylene is filtered and the latter returned to the cycle. The initial acrylonitrile layer containing from 4 to 5% of water is fractionated in a fractionating still operating with substantially total reflux of the nitrile. The water and nitrile form an azeotropic mixture in the reflux column. Over a temperature range of from 70 to 75° C. this reflux mixture is condensed at the reflux head and allowed to stratify into two layers. The upper nitrile layer is returned to the still while

the lower water layer is withdrawn and returned to an initial water layer containing some acrylonitrile. A small amount of nitrile polymer forms during the fractionation. The acrylonitrile from the xylene extraction of the initial water layer is added to the still content. A fraction of wet acrylonitrile is then removed at a temperature of from 75 to 77° C. and returned to an initial acrylonitrile layer containing water. The dry acrylonitrile is distilled from the polymer residue 10 at a temperature of from 77 to 78° C.

In refining a crude olefinic nitrile such as, for example, crude acrylonitrile, as illustrated by the flow sheet of Fig. 3, the crude product is allowed to separate into two layers. The lower layer of water containing some nitrile is withdrawn and discarded. The upper acrylonitrile layer containing some water is fractionated in a fractionating still operating with substantially total reflux of the nitrile. The water and acrylonitrile form an azeotropic mixture in the reflux column. Over a temperature range of from 70 to 75° C. this mixture is condensed at the reflux head and allowed to stratify into two layers. The upper nitrile layer flows back into the still while the lower water layer is withdrawn and discarded. A fraction of wet acrylonitrile is then removed at a temperature of from 75 to 77° C. and returned to an initial acrylonitrile layer containing water. The dry acrylonitrile is distilled from the polymer residue at a temperature of from 77 to 78° C.

In employing the procedure outlined by the flow sheet of Fig. 3, a crude crotonic nitrile-water mixture, produced for instance by the dehydration of propylene cyanohydrin, is permitted to separate into two layers. The lower layer of water containing some crotonic nitrile is withdrawn and discarded. The upper layer which is predominantly crotonic nitrile containing some water is dried by azeotropic distillation from a fractionating still. The water and crotonic nitrile form an azeotropic mixture boiling at a temperature of about 85° C. which is condensed at the reflux head of the still and permitted to stratify into two layers. The upper crotonic nitrile layer is returned to the still while the lower water layer is removed and discarded. The cis- and trans-crotonic nitrile isomers are thereafter fractionally distilled from the still content at the temperatures of 107.5-108.5° C. and 119.0-120.5° C. respectively.

Olefinic nitrile solvents which are immiscible with water, such as benzene, toluene, xylene and the like are suitable for the extraction of the olefinic nitrile from the water layer.

Other members of the olefinic nitrile series in similar crude form may be refined according to the method herein described, using appropriate temperatures dependent upon the nitrile chosen.

While the invention has been described with particular reference to specific embodiments, it is to be understood that it is not to be limited thereto but is to be construed broadly and restricted solely by the scope of the appended claims.

We claim:

1. A method of refining a crude olefinic nitrile containing water which comprises separating the product into two layers, the upper of which is predominantly nitrile containing some water while the lower layer is predominantly water containing some nitrile, extracting the nitrile from said lower layer by means of a hydrocarbon solvent, combining the solvent extract and upper nitrile layer, permitting the mix to stratify, re-

moving the lower water layer displaced by the hydrocarbon solvent and returning the same to a subsequently produced initial water layer containing nitrile, distilling the major portion of the remaining water from the hydrocarbon solvent-nitrile mixture and returning said water distillate to the above mentioned and subsequently produced initial water layer containing nitrile, subsequently fractionally distilling a wet nitrile fraction from the hydrocarbon solvent-nitrile mixture and returning said nitrile fraction to a subsequently produced initial nitrile layer containing water, thereafter fractionally distilling the dry olefinic nitrile from the hydrocarbon solvent-polymer residue, separating the polymer and hydrocarbon solvent, and returning the latter to the cycle for extraction of nitrile from a subsequently produced and initial lower layer predominantly water but containing some nitrile.

2. A method of refining crude acrylonitrile containing water which comprises separating the product into two layers, the upper of which is predominantly acrylonitrile containing some water while the lower layer is predominantly water containing some acrylonitrile, extracting the acrylonitrile from the said lower layer by means of xylene, combining the xylene extract and upper acrylonitrile layer, permitting the mix to stratify, removing the lower water layer displaced by the xylene and returning the same to a subsequently produced initial water layer containing acrylonitrile, distilling the major portion of the remaining water from the xylene-acrylonitrile mixture at a temperature of from 70 to 75° C., and returning the said water distillate to the above and subsequently produced initial water layer containing acrylonitrile, subsequently fractionally distilling a wet acrylonitrile fraction from the xylene-acrylonitrile mixture at a temperature of from 75 to 77° C., and returning said acrylonitrile fraction to a subsequently produced initial acrylonitrile layer containing water, thereafter fractionally distilling the dry acrylonitrile from the xylene-polymer residue at a temperature of from 77 to 78° C., separating the polymer and xylene and returning the latter to the cycle for extraction of acrylonitrile from a subsequently produced and initial lower layer predominantly water but containing some acrylonitrile.

3. A method of refining a crude olefinic nitrile containing water which comprises separating the product into two layers, the upper of which is predominantly nitrile containing some water while the lower layer is predominantly water containing some nitrile, extracting the nitrile from said lower layer by means of a hydrocarbon solvent, distilling the nitrile from the hydrocarbon solvent, separating the still residue of polymer and hydrocarbon solvent and returning the latter to the cycle, distilling the major portion of the water from the initially produced upper nitrile layer and returning said water distillate to a subsequently produced initial water layer containing nitrile, adding to the nitrile layer remaining from the major water removal step, the nitrile from the hydrocarbon solvent extract to form a nitrile mixture, subsequently fractionally distilling a wet nitrile fraction from the said nitrile mixture and returning said nitrile fraction to an initial nitrile layer containing water, thereafter fractionally distilling the dry olefinic nitrile from the polymer residue.

4. A method of refining crude acrylonitrile containing water which comprises separating the

product into two layers, the upper of which is predominantly acrylonitrile containing some water while the lower layer is predominantly water containing some acrylonitrile, extracting the acrylonitrile from the said lower layer by means of xylene, distilling the acrylonitrile from the xylene, separating the still residue of polymer and xylene and returning the latter to the cycle, distilling the major portion of the water from the upper acrylonitrile layer at a temperature of from 70 to 75° C. and returning said water distillate to a subsequently produced initial water layer containing acrylonitrile, adding to the remaining acrylonitrile layer the acrylonitrile from the xylene extract to form an acrylonitrile mixture, subsequently fractionally distilling a wet acrylonitrile fraction from the acrylonitrile mixture at a temperature of from 75 to 77° C. and returning said acrylonitrile fraction to an initial acrylonitrile layer containing water, thereafter fractionally distilling the dry acrylonitrile from the polymer residue at a temperature of from 77 to 78° C.

5. A method of refining a crude olefinic nitrile containing water which comprises separating the product into two layers, the upper of which is predominantly nitrile containing some water while the lower layer is predominantly water containing some nitrile, distilling from the upper nitrile layer an azeotropic mixture of nitrile and water, subsequently fractionally distilling a wet nitrile fraction therefrom and returning the same to a subsequently produced initial nitrile layer containing water, thereafter distilling the dry olefinic nitrile from the polymer residue.

6. A method of refining crude acrylonitrile containing water which comprises separating the product into two layers, the upper of which is predominantly acrylonitrile containing some water while the lower layer is predominantly water containing some acrylonitrile, distilling from the upper acrylonitrile layer an azeotropic mixture of acrylonitrile and water until the distillate temperature has risen from 70° C. to 75° C., subsequently fractionally distilling a wet acrylonitrile fraction therefrom at a temperature of from 75-77° C. and returning the same to a subsequently produced initial acrylonitrile layer containing water, thereafter distilling the dry acrylonitrile from the polymer residue at a temperature of from 77 to 78° C.

7. A method of refining crude crotonic nitrile containing water which comprises separating the product into two layers, the upper of which is predominantly crotonic nitrile containing some water while the lower layer is predominantly water containing some crotonic nitrile, distilling from the upper crotonic nitrile layer an azeotropic mixture of crotonic nitrile and water until the crude crotonic nitrile is substantially dehydrated, subsequently distilling a wet crotonic nitrile fraction therefrom to remove the remaining water and returning this fraction to a subsequently produced initial crotonic nitrile layer containing water, and thereafter fractionally distilling the cis- and trans-crotonic nitrile isomers at the temperatures of 107.5-108.5° C. and 119.0-120.5° C. respectively.

8. A method of refining a crude olefinic nitrile containing water to remove water therefrom which comprises distilling therefrom an azeotropic mixture of the nitrile and water, condensing the distillate, permitting the condensed distillate to stratify into an upper wet nitrile layer and a lower water layer, separating off the water

layer, returning the wet nitrile layer to the distilland for recycling and finally collecting the substantially dehydrated nitrile.

9. A method of refining a crude acrylonitrile containing water to remove water therefrom which comprises distilling therefrom an azeotropic mixture of the acrylonitrile and water, condensing the distillate, permitting the condensed distillate to stratify into an upper wet acrylonitrile layer and a lower water layer, separating off the water layer, returning the wet acrylonitrile layer to the distilland for recycling and finally collecting the substantially dehydrated acrylonitrile.

10. A method of refining a crude crotonic nitrile containing water to substantially dehydrate the same which comprises distilling therefrom an azeotropic mixture of the crotonic nitrile and water, condensing the distillate, permitting the condensed distillate to stratify into an upper wet crotonic nitrile layer and a lower water layer, separating off the water layer, returning the wet crotonic nitrile layer to the distilland for recycling and finally collecting the substantially dehydrated crotonic nitrile.

11. In the method of refining a crude olefinic nitrile containing water to substantially dehydrate the mixture, the process which comprises placing the crude nitrile in a still provided with a fractionating column and a condenser, distilling an azeotropic mixture of nitrile and water from the crude nitrile, passing the vapor distillate through the fractionating column and into the condenser, condensing the distillate, allowing the distillate to stratify into an upper nitrile layer substantially saturated with water, and a lower water layer, drawing off the water layer, and returning the wet nitrile to the fractionating column, and finally collecting the substantially dehydrated nitrile.

12. In the method of refining a crude acrylonitrile containing water to substantially dehydrate the mixture, the process which comprises placing the crude acrylonitrile in a still provided with a fractionating column and a condenser, distilling an azeotropic mixture of acrylonitrile and water from the crude acrylonitrile, passing the vapor distillate through the fractionating column and into the condenser, condensing the distillate, allowing the distillate to stratify into an upper acrylonitrile layer substantially saturated with water, and a lower water layer, drawing off the water layer, and returning the wet acrylonitrile to the fractionating column, and finally collecting the substantially dehydrated acrylonitrile.

13. In the method of refining a crude crotonic nitrile containing water to substantially dehydrate the mixture, the process which comprises placing the crude crotonic nitrile in a still provided with a fractionating column and a condenser, distilling an azeotropic mixture of crotonic nitrile and water from the crude crotonic nitrile, passing the vapor distillate through the fractionating column and into the condenser, condensing the distillate, allowing the distillate to stratify into an upper crotonic nitrile layer substantially saturated with water, and a lower water layer, drawing off the water layer, and returning the wet crotonic nitrile to the fractionating column, and finally collecting the substantially dehydrated crotonic nitrile.
